UNITED STATES PATENT OFFICE

JOHN WEBER, OF MILTON, PENNSYLVANIA

DESIGN FOR A CEDAR CHEST OR SIMILAR ARTICLE

Application filed July 15, 1932. Serial No. 44,339. Term of patent 3½ years.

To all whom it may concern:

Be it known that I, JOHN WEBER, a citizen of the United States, residing at Milton, Northumberland County, Pennsylvania, have invented a new, original, and ornamental Design for a Cedar Chest or Similar Article, of which the following is a specification, reference being had to the accompanying drawing, forming a part thereof.

The figure is a perspective view of a cedar chest or similar article, showing my invention.

I claim:

The ornamental design for a cedar chest or similar article, as shown.

In witness whereof, I hereunto subscribe my name this 20th day of May, 1932.

JOHN WEBER.
